UNITED STATES PATENT OFFICE.

EDWIN N. OLSON, OF BELLINGHAM, WASHINGTON.

POTATO-STRIPPER.

1,154,539.

Specification of Letters Patent. Patented Sept. 21, 1915.

Application filed July 3, 1915. Serial No. 37,875.

To all whom it may concern:

Be it known that I, EDWIN N. OLSON, a citizen of the United States, residing at Bellingham, in the county of Whatcom and 5 State of Washington, have invented certain new and useful Improvements in Potato-Strippers; and I do hereby declare the following to be a full, clear, and exact description of the invention, such as will enable 10 others skilled in the art to which it appertains to make and use the same.

One object of this invention is to admit of the cutting of potatoes and similar articles into oblong strips, for various purposes.

Another object is to provide a cutting means for carrying out the above operation, that will insure of the complete severance of the strips; also of the cutting of the strips 20 into different thicknesses when desired.

A further object of the invention is to insure of the guiding of the article, to be cut, into the path of a cutting mechanism, whereby to admit of the cutting into strips 25 of the entire article.

Other objects will appear and be better understood from that embodiment of my invention of which the following is a specification, reference being had to the accompanying drawings forming a part thereof, in which:

Figure 1 is a perspective view of the stripper, Fig. 2 is a side elevation of the cutting side of the stripper, Fig. 3 is an end view taken on the line 4—4 of Fig. 1, Fig. 35 4 is a cross section through the stripper, showing the cutting end thereof and with the cutting mechanism removed, Fig. 5 is a perspective view of the cutting mechanism 40 removed from the body of the stripper, and Fig. 6 is a detail sectional view taken through the cutting portion of the cutting mechanism shown in Fig. 5.

Referring to the drawings more in detail, 45 the letter A designates the stripper as an entirety, and which includes a trough 1, which is formed in part, from a substantially rectangular piece of metal bent upon itself to provide an inclined wall 2 and vertical wall 3, the latter wall having a rectangular opening 4 therein, so as to provide a frame formed of the vertical side members 5 and 6 and an upper longitudinally extending top piece 7 which connect the side pieces 5 and 6 and which is extended angularly 55 to the side pieces 5 and 6, as shown at 8,

for a purpose to be hereinafter referred to. The sides 5 and 6 are connected to the ends of the inclined wall 2 by means of end pieces 9 and 10. The main body portion of the end piece 9 lies flush with the edges of the adjacent side piece 5 and the edge of the inclined wall 2, and has its opposite end bent inwardly to provide attaching flanges 11 and 12, which engage respectively, the inner surfaces of the side piece 5 and the inclined wall, and are secured thereto by fastening means 13. The end piece 10 is positioned at a point inwardly of the adjacent end of the trough, and has its opposite ends provided with attaching flange 14, which is secured to the inner surface of the inclined wall 2 by fastening means 15, the opposite edge of the end piece 10 being secured to the adjacent side piece 6 in any suitable manner. The inclined wall 2 has its lower longitudinal edge provided with a vertically depending portion 16, which extends a considerable distance below the side portions 5 and 6 and carries a longitudinally extending strip 17, which is located directly below the angularly extending portion 8 on the top piece 7. The strip 17 is substantially L-shaped in cross section, as shown in Fig. 4 so as to provide a race or guideway 18. 85 The angularly extending portion 8 on the top piece 7 has its under surface provided with a longitudinally extending strip 20, which extends throughout the length of the top piece 8 and is of a width less than the portion 8 and is positioned adjacent the outer longitudinal edge of the said portion to provide a guideway 21 which is in vertical alinement with the guideway 18.

Slidably mounted within the guideways 95 18 and 21, is a stripper 22. This stripper is formed of an elongated metallic plate, which is bent to provide the guide plates 24 and 25, which extend in parallel relation. The guide plates 24 and 25 are provided at the point of juncture with a vertical opening 26, which opening extends a distance into the guide plate 24, and provides at the opposite longitudinal edges of the guide plates 24 and 25, a pair of angularly connecting portions 100 27 and 28, which portions 27 and 28 connect the said guide plates 24 and 25. Located within the opening 26, is a cutter carrying plate 29. This cutter carrying plate is of substantially U-shaped configuration, and 105 has its bight portion 30 lying flush with one of the adjacent guide plates, and the sides

of the cutter carrying plate have oppositely extending flanges 31 and 32 which overlie the angular connecting portions 27 and 28 and are secured thereto by the fastening elements 33. The outer side of the guide plate 24, is provided with a pair of longitudinally extending strips 34 and 35, which are located on the plate at the longitudinal edges and engage the outer surface of the angularly connecting portions 27 and 28, and are secured thereto by the fastening elements 33, and are adapted to be loosely received by the guideways 18 and 20, so as to admit of the guides 24 and 25 to have sliding movement within the said guideways 18 and 21. The cutter carrying plate 29 is provided with a series of spaced slots 36, which are adapted to receive a plurality of U-shaped cutters 37, the eight portions of the cutters being secured to those portions of the cutter carrying plates, which is located between the slots, by means of fastening elements 38, the said U-shaped cutters having side portions projecting into the slot or vertical opening in the guide plate 24 and beyond the adjacent surface of the said guide plate and provided with the cutting edges 39. The handle carrying plate has a vertically disposed cutting knife 40, which lies flush with the plate 24, and overlies the terminals of the sides of the U-shaped cutters and has its opposite ends secured to the flanges 31 and 32 of the cutter plate 39, by means of a fastening element 41.

35 The inner surface of the connecting end piece 10 is provided with a substantially triangular shaped plate 42, which is secured to the said connecting end piece 10 by means of fastening elements 43. This plate 42 has its enlarged end projecting through the opening 4 in the adjacent wall of the trough, and formed with a series of slots 43', which open into the adjacent ends of the plate 42 and into the opposite sides of the said plate, and are located in alignment with the cutting edges of the U-shaped fasteners 27. The side piece 6 of the frame has its inner edge provided with a series of laterally projecting fingers 44 which are adapted to engage the outer sides of those portions of the plate 42, which are located between the slots 43' and provide reinforcing means for said portions. The plate 25 is provided with a longitudinally extending rib 45, which reinforces the plate against outward strain, and the said plate has its free terminal extended outwardly as shown at 46, so as to not interfere with the end of the plate 42, during the sliding of the guides.

50 The inclined wall 2 of the trough has depending therefrom an angularly shaped plate 47. This plate 47 has its upper flanged side 48 secured to the inclined wall 2 by means of the fastening elements 49, and

has its lower flanged portion projecting in the direction of the depending vertical portion 16 on the lower edge of the inclined wall 2. The plate 47 has secured thereto the longer arm of an L-shaped bracket 51, the shorter arm extending below the portion 50 and spaced therefrom, and provided with a screw clamp 52. The portion 50 and the screw clamp 52 are adapted to receive therebetween the edge of a table top or similar support, and the screw clamp is adapted to be engaged thereagainst so as to hold the device in position.

In the operation, the article to be cut or stripped, is placed within the trough and by virtue of the inclined wall 2, the article will be moved into the path of the U-shaped cutters. When the stripper cutters and guides are moved in the direction of the plate 42, the sides of the U-shaped cutters and the knife 40, will during their travel, cause the articles to travel in the same direction until the article engages the plate 42, the article will be arrested and the continued travel of the U-shaped knives will result in the severing of the articles at spaced points and into oblong strips. The strips as cut from the article, will be forced between the sides of the U-shaped cutters and out through the space between the cutter carrying plate 29 and the guide plate 24, and deposited on the table or other support, or into a dish so disposed to receive the severed strips. As a means for moving the guides 24 and 25, so as to effect the cutting of the article, a handle 53 is provided. This handle has one end secured to the plate 24, and has its opposite end projecting laterally and angularly from the plate, as shown in Fig. 3, to admit of the convenient operation of the guide plates 24 and 25.

Having thus described my invention, what I claim as new is:—

1. A device of the class described comprising, a trough having one of its sides opened and having its opposite side inclined, a plate mounted within the trough and adjacent one end of the trough, and having one of its edges projecting through the open side and provided with a plurality of spaced slots, and a cutter carrying plate slideable across the open side of the trough and provided with a plurality of spaced cutters alining with the slots in the plate, and a vertically disposed knife associated with the cutter carrying plate and resting upon the first mentioned cutters.
2. A device of the class described comprising, a trough having one of its sides open, guide plates slideable across the opened side of the trough and having connection with each other and arranged in offset relation, a cutter plate associated with the guide and lying flush with one of the guide plates and disposed beyond the other guide plates, U-

shaped cutters carried by said cutter carrying plates, a vertically disposed knife carried by the cutter carrying plate and overlying the U-shaped cutters, and a plate located within the trough and having one end projecting through the open side of the trough and provided with a plurality of spaced slots, the said slots in the end of the plate being alined with the U-shaped cutters.

10 3. A device of the class described comprising a trough having one of its sides provided with an opening, guideways formed on the trough and located above and below the opening, guide plates slidable within the guides and across the opening and arranged in offset relation and connected to each other, a cutter plate associated with the guide plates, cutters carried by the cutter carrying plates, a plate located within the trough and having one end projecting through the opening in the side of the trough and provided with a plurality of slots, said slots in the plate being alined with the cutters on the cutter carrying plates, a vertically disposed

15 25 25 knife associated with the cutter carrying

plates and overlying the first mentioned cutters, and a manipulating handle carried by one of the guide plates.

4. A device of the class described comprising, a trough having one of its sides open, guideways formed on the trough and located above and below the open side, guide plates slidably mounted within the guideways and slideable across the open side and connected to each other, a plurality of cutters carried by the guide plates, one of the plates having a longitudinally extending rib formed thereon, and having one of its terminals extended angularly, and a plate located within the trough and having one end extending through the opening in the open side of the trough and provided with a plurality of slots, the said slots being arranged in alinement with the said cutters.

In testimony whereof I affix my signature in presence of two witnesses.

EDWIN N. OLSON.
